UNITED STATES PATENT OFFICE.

JOHN P. SHEARER, OF NYACK, NEW YORK.

ELECTRIC SIGN.

No. 905,468.

Specification of Letters Patent.

Patented Dec. 1, 1908.

Application filed April 16, 1908. Serial No. 427,527.

To all whom it may concern:

Be it known that I, JOHN P. SHEARER, a citizen of the United States, and a resident of Nyack, in the county of Rockland and State of New York, have made and invented certain new and useful Improvements in Electric Signs, of which the following is a specification.

My invention relates to an improvement in electric signs, and more especially to that type or kind thereof which is adapted for outdoor use, the object being to construct a sign of this character in which the interior wiring will be protected from water, thereby avoiding all danger of short circuits or leakage of electricity which might occur, should the wiring or lamp sockets become wet.

Further objects of my invention are to provide a device of this character which will be economical to construct; which will be light proof; which will permit of ready access to its interior, whereby the lamps may be changed when burned out, and any repairs to the wiring or sockets may be quickly made; and from which the panels may be easily and quickly removed or inserted when it is desired to change them or to replace a broken one.

With these and other ends in view, my invention consists in certain novel features of construction and combinations of parts, as will be hereinafter fully described and pointed out in the claims.

In the accompanying drawings Figure 1 is a perspective view of my improved sign. Fig. 2 is a vertical sectional view thereof. Fig. 3 is a sectional view taken on the line 3—3 of Fig. 2. Fig. 4 is a sectional view taken on the line 4—4 of Fig. 2. Fig. 5 is a perspective view of the top or upper section. Fig. 6 is a perspective view of the lower section comprising the bottom and end members. Fig. 7 is a sectional view taken on the line 7—7 of Fig. 2.

Referring to the drawings, 8 indicates the casing of the sign which is preferably made in two parts or sections 9 and 10, the section 9 being the top or cover of the casing and the section 10 comprising the bottom and end portions thereof, said sections or parts being preferably formed from suitable sheet metal. The section 10 comprises the bottom member 11 and the upwardly bent

or turned end members 12 and 12, all of said members being provided with inwardly extending side portions 14 and 15, which are formed by bending the metal inward, and at the inner edges of said side portions, the metal is bent backward and then outward upon itself to form the grooves or channels 16 and 17 with which the panels 18 are adapted to have sliding engagement, and by which they are supported in position, as clearly indicated in Figs. 2, 3 and 4. These panels may be made of glass or any other transparent or translucent material, or they may be made of metal and provided with cut out portions protected or covered by glass or other suitable material through which the light is permitted to pass. Suitable openings 18^a are provided in the bottom 11, whereby water, which may creep into the sign, is permitted to escape therefrom and to provide for a circulation of air, and over these openings are placed caps or coverings 19 of any appropriate shape, which are retained in place by solder or any other suitable means, and which serve to prevent light from escaping through said openings.

The top or upper section 9 is provided at 80 its sides with inwardly extending side portions 20 provided with grooves or channels 21 similar in all respects to the side portions 14 and 15 and the grooves 16 and 17 formed on the lower section 10, and at its 85 ends, said section is provided with downwardly extending flanges 22. Openings 23 are preferably formed in the top section 9 for the purposes of ventilation, and covering said openings is a suitable cover or cap 24, 90 preferably channel shaped, as shown, and adjacent the ends of said cap and extending between the sides thereof are the end pieces or stops 25, this construction of cover and end stops, effectually preventing rain or 95 snow from passing through the openings 23 into the interior of the sign, and also preventing the light from passing out. When the top section is placed in position upon the bottom section the flanges 22 will engage 100 the outer surfaces of the end members 12 and the side portions 20 thereof will engage with the outer surface of the side members 15, as shown in Figs. 2 and 7. The sections are secured or fastened together in any suitable manner, as for example by bolts or

screws 26 passing through the registering holes 27 and 28 formed in the side portions 15 and 20, respectively, and engaging nuts 29, which may be secured to the inner surfaces of the side portions 15, as clearly shown in Fig. 7. The grooves 21 will engage the upper edges of the panels 18, as shown in Fig. 4. When it is desired to remove the top section 9 for any reason, it is simply necessary to remove the screws 26, after which the top may be lifted off, thus providing for quick and ready access to the interior of the sign.

It will be seen from the above description that the joint between the upper and lower sections of the casing is water tight, owing to the fact that the side members 20 and end flanges 22 of the top section extend outside and engage the outer surfaces of the sides 15 and end members 12, thereby rendering it impossible for water to work in between the sections. Should any water creep in between the panels 18 and the supporting grooves or channels, it will be led by said grooves or channels to the lower part of the casing from which it will escape through the openings 18^a in the bottom member 11.

Extending between the end portions 12 of the casing 8 is a removable socket-supporting bracket 30 carrying the lamp sockets 31 and lamps 32, and suitable connecting wires 33, which wires pass out of the casing through suitable bushings 34, located in one of the end members 12 and preferably formed of insulating material. While the bracket 30 may be removably supported within the casing in any suitable manner, I have shown it as being provided with bent ends 35 adapted to engage the inner surfaces of the end members 12, with which it is held in engagement by means of screws or bolts 36 passing through registering openings in said end members and bent ends, and engaging with nuts 37, as clearly shown in Fig. 2.

From the above description it will be understood that if it is desired to remove the bracket 30 for any reason, it is simply necessary to first remove the top section 9 in the manner hereinbefore described, and then remove the bolts or screws 36 and nuts 37, after which the bracket 30 may be bodily withdrawn from the interior of the casing carrying with it, of course, the sockets, lamps and interior wiring. The panels 18 may be withdrawn from or inserted within their supporting grooves or channels, after the top section has been removed, if it is desired to change them or replace them when they have become broken or damaged in any way.

The sign may be supported by any suitable means, such as the straps 38 secured to the end members 12 in any suitable manner,

said straps being bent slightly outward in ⁶⁵ order that the flange 22 may pass between the same and the end members 12, as shown in Fig. 2. Of course I do not wish to limit, to this form of support, as any other form may be used in connection with my sign ⁷⁰ without in any way departing from the spirit of my invention.

Having fully described my invention, what I claim as new and desire to secure by Letters Patent, is:—

1. In a sign of the character described, a casing consisting of a top and bottom section each formed of a single piece of material, said bottom section comprising a bottom portion, with parallel sides having inturned ⁸⁰ edges fashioned with a groove or channel, and integral parallel ends with inwardly-turned sides whose edges are fashioned with grooves or channels; said top section comprising a top portion with integral sides and ⁸⁵ ends, said sides of the top section having inturned edges fashioned with grooves or channels, and the ends of the top section overlapping on the outside the corresponding ends of the bottom section; parallel panels having ⁹⁰ their edges fitting the grooves or channels in the top and bottom sections; and means for detachably uniting said sections.

2. In a sign of the character described, a casing consisting of top and bottom sections ⁹⁵ each formed of a single piece of metal, said bottom section including a bottom member with up-turned sides and parallel and equal ends with inturned sides; said top member including a top portion with downturned ¹⁰⁰ sides and ends, the upturned sides of the bottom and the inturned sides of the ends of the bottom section and the downturned sides of grooves or channels; said downturned edges turned and bent to form grooves or ¹⁰⁵ channels; panels having edges fitting the said grooves or channels; said downward edges of the ends of the top section fitting over the outside of the ends of the bottom section; and means detachably uniting the top and ¹¹⁰ bottom sections.

3. In a sign of the character described, a casing consisting of top and bottom sections, said bottom section having a bottom and end portions each provided with grooves or channels, and said top section having a top and ends and having grooves or channels coinciding with those in the bottom section, panels mounted in said grooves, fastenings detachably uniting the top and bottom section ¹¹⁵ and permitting access to the panels from the top of the casing, and a lamp supported in the casing.

4. In a sign of the character described, a casing consisting of a top and bottom, said bottom section having a bottom portion and parallel ends; said top section being detachably fitted over the ends of the bottom sec-

tion; panels mounted in the casing; a bar insertible through the open top of the bottom section and having flanges fitting against the sides of the bottom section; detachable fastenings for said bar; and a lamp support carried by the bar.

Signed at New York borough of Manhat-

tan in the county of New York and State of New York this 14" day of April, A. D. 1908.
